UNITED STATES PATENT OFFICE.

JOHN T. AUSTIN, OF HARTFORD, CONNECTICUT, ASSIGNOR TO THE AUSTIN ORGAN COMPANY, OF HARTFORD, CONNECTICUT, A CORPORATION OF CONNECTICUT.

SWELL-SHUTTER-CONTROLLING MECHANISM.

Application filed February 3, 1925. Serial No. 6,511.

This invention relates to swell shutter controlling mechanism for automatic organs, such as pipe organs, and has as its object to provide an improved arrangement where-
5 in the swell shutter or fold means may be automatically controlled by a perforated music sheet with great nicety to effect the desired variations and changes in the volume of the tones produced within the swell box.

10 My improved arrangement is characterized by its extreme simplicity in construction, by the fact that but a single opening or hole in the tracker bar, over which the music sheets pass, is required in connection
15 with the shutter controlling mechanism, and by its effectiveness in operation, particularly in that any desired intensity of sound within the capacity of the swell box may be obtained and the variations in intensity may
20 be effected very gradually.

In the present illustrative disclosure, the music sheet, which controls the playing mechanism, has an irregular or wavy edge of such contour as to control the hole with-
25 in the tracker bar associated with the shutter mechanism, so that the latter is opened or closed in accordance with the desired variations in loudness. My invention also
30 resides in the music sheet itself.

35 In the accompanying drawing, I have shown, more or less diagrammatically, one embodiment which the invention may take, it being obvious that this disclosure is by way of exemplification only, and that the structure is susceptible of various modifi-
40 cations and changes which would be within the spirit of the invention without departing from the scope of the appended claims; for example, in this drawing, the pneumatic for
45 operating the shutter or shutters is shown as being directly controlled from the tracker bar, but, if desired, the means for operating the shutters may be in part electric and in part pneumatic, and, if preferred, the pneumatic illustrated may be controlled through a primary bellows. Various other arrangements may be adopted.

In said drawing:

50 Figures 1 and 2 show diagrammatic organizations with the shutters in closed and partly open positions, respectively.

Referring to the drawing in detail, 10 designates a tracker bar having the usual holes 11, and 12 is a note sheet adapted to

55 pass over the tracker bar from one roll 13 to the other one and having note playing perforations 14. The swell box, designated by the numeral 15, has an opening 16 in which is mounted the means for varying the volume of the sound and which means may 60 be in the form of a pivoted shutter or a plurality of shutters 17 connected together by a rod 18. In the present illustrative disclosure, the shutter means is normally urged 65 into open position by a tension spring 19 connected to the upper end of the rod 18, and the closing of the shutters against the tension of this spring is effected through a pneumatic or bellows 20. It is understood, 70 however, that this arrangement may be reversed; that is to say, a spring may be employed to normally urge the shutters into closed position and a pneumatic may be used for opening the shutters.

75 The pressure within the pneumatic is controlled by the note sheet 12, and to this end, the note sheet is provided with a wavy or irregular edge 22 adapted to cooperate with a port 23 in the end of the tracker bar and connected by a tube 24 to the pneumatic 20. The pneumatic is connected by a bleed 25 to an exhaust pipe or chamber 26. The bleed 25 is smaller than the opening through the tube 24, so that a range in pressure within 80 the pneumatic from substantially atmospheric pressure, when the port 23 is totally uncovered, to the pressure obtaining within the exhaust chamber 26, when the port 23 is totally covered, may be had.

85 The operation of the arrangement de-
90 scribed is briefly as follows: It is understood that the music sheet will be so constructed that the edge 22 thereof will undulate or curve in accordance with the increases and decreases in volume desired during the ren-
95 dition of the selection. In those places where gradual changes in volume are want-
ed, the edge of the sheet will be gradually or slightly curved or inclined to the direc-
100 tion of travel of the sheet, and in case of de-
sired quick changes in volume the edge will be more abruptly curved or inclined. As the music sheet passes over the tracker bar, the edge 22 of the former will control the admission of atmospheric pressure to the 105 pneumatic or bellows 20. When the music sheet entirely closes the port 23, as shown in Fig. 1, the pressure within the pneumatic

or bellows 20 is brought substantially to that obtaining within the exhaust chamber 26, so that the bellows is collapsed against the force of the spring 19 and the shutters are moved in closed position. As the music sheet proceeds over the tracker bar from the position shown in Fig. 1 to that shown in Fig. 2, the port 23 is gradually uncovered by the music sheet, permitting the air to pass through the tube 24 to the pneumatic, with the result that, as the force of suction within the pneumatic is gradually reduced, the shutters, under the influence of the spring 19, will gradually open, which means that the musical sound issuing from the swell box will gradually increase in volume. When the port 23 is totally uncovered by the music sheet, as would be the case when the music sheet advances to the dotted line position shown in Fig. 2, the pressure within the pneumatic will be substantially the same as atmospheric pressure, and the spring 19 will move the shutters to full open position shown by dotted lines. It will be observed that the pull of the pneumatic on the shutters and spring 19 gradually grows less as the pneumatic collapses, because, as the pneumatic does collapse, the folds thereof offer greater resistance to the force of suction therein. As the pneumatic collapses, the force of the spring becomes greater owing to its expansion. The result is that the pneumatic and shutters will retain the various positions which they are caused to assume, so long as the pressure within the pneumatic remains constant.

From the foregoing description, taken in connection with the drawing, it will be seen that my invention provides for the utmost flexibility in the control of the expression of the tonal qualities of the pipes enclosed in the swell box. The volume of the sound issuing from the swell box may be gradually or abruptly changed so as to give the desired effects. This is brought about in a very simple and effective manner.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense. If desired, each of the side edges of the music sheet may be irregular or wavelike, and shutter means for two

swell boxes may be controlled by the respective edges.

It is also to be understood that the language used in the following claims is intended to cover all of the generic and specific features of the invention herein described and all statements of the scope of the invention which, as a matter of language, might be said to fall therebetween.

I claim as my invention:

1. In combination, a swell box, shutter means therefor, operating means associated therewith, and means for controlling said operating means and including a music sheet with an irregular edge corresponding to the desired variations in the sound effected by said shutter means.

2. In combination, a swell box, shutter means therefor, operating means associated therewith, a tracker bar having a port through which said operating means is governed, and a music sheet adapted to pass over the tracker bar and having an uneven edge controlling said port.

3. In combination, a swell box, shutter means therefor, pneumatic means operatively associated therewith, a tracker bar having a port through which said pneumatic means is governed, and a music sheet having a wavy edge controlling said port.

4. In combination, a swell box, shutter means therefor, a pneumatic operatively connected with said shutters, an exhaust chamber, said pneumatic having a bleed opening leading to said chamber, a tracker bar having a port communicating with said pneumatic, and a note sheet controlling said port.

5. In combination, a swell box, shutter means therefor, bellows operatively associated with said shutter means, a spring connected to said shutter means, and a tracker bar having a port through which said bellows is governed, said bellows and spring working in opposition and being substantially balanced in all positions of said shutters while the pressure within the bellows is constant.

6. In combination, a swell box, shutter means therefor, a spring normally urging said shutter means to one position, pneumatic means operatively associated with said shutter means and acting in opposition to said spring, a tracker bar having a port through which said pneumatic means is governed, and a music sheet having a wavy edge controlling said port.

JOHN T. AUSTIN.
